PUFFED TEXTILE FABRIC

Clement R. Howell, Winnsboro, S.C., assignor to United States Rubber Company, New York, N.Y., a corporation of New Jersey

Application November 29, 1957, Serial No. 48,716

Term of patent 14 years

(Cl. D92—1)

Fig. 1

Fig. 1 is a plan view of a puffed textile fabric showing my new design; and

Fig. 2 is a sectional view of the fabric of Fig. 1 along the line 2—2.

The design is embodied in a puffed textile fabric having a surface provided with a plurality of puffs appearing as ridges with irregular sides. In the embodiment shown, the puffs are held raised by threads interlaced in the fabric as represented by the straight line in Fig. 2.

I claim:

The ornamental design for a puffed textile fabric, as shown and described.
